LOUIS L. WHITE, OF DORRIS, CALIFORNIA, ASSIGNOR TO PLATINUM ELECTRIC INCUBATOR COMPANY, OF DORRIS, CALIFORNIA, A CORPORATION OF CALIFORNIA.

ELECTROMAGNETIC SWITCHING SYSTEM.

1,123,452.

Specification of Letters Patent.

Patented Jan. 5, 1915.

Application filed November 4, 1912. Serial No. 729,462.

To all whom it may concern:

Be it known that I, LOUIS L. WHITE, a citizen of the United States, residing at Dorris, in the county of Siskiyou and State of California, have invented new and useful Improvements in Electromagnetic Switching Systems, of which the following is a specification.

This invention relates to electric systems, and particularly to an electrical apparatus involving a circuit and means for controlling the opening and closing of said circuit, said means being sensitive to variations of temperature.

15 It is an object of the invention to provide an electric circuit adapted to be thermostatically controlled; the thermostatic apparatus being designed to operate to close a circuit in which may be mounted mechanism which 20 it is desired to actuate at times when there is a variation of temperature.

A further object of the invention is to provide a simple, reliable, automatic electromagnetic mechanism, designed to operate 25 without sparking during the breaking of the circuit at the thermostat.

30 A further object is to provide an electro-magnetically operated main circuit switch and a mechanical, positive, electrically operated lock for the switch.

The invention consists of the parts and the construction and combination of parts as hereinafter more fully described and claimed, having reference to the accompanying drawing, in which the figure is a dia- 35 grammatic view of the apparatus.

My thermostatic apparatus comprises a U-shaped thermometer tube 2 ending in bulbs 3 and 4. Each leg of the tube is graduated and has conductor terminals 6 for each of the several graduations thereof. The conductors 6 are provided with sockets 11 into which an adjustable plug 10 may be inserted. The plugs 10 are adapted to contact with ground conductors 7 which are provided with binding posts 8 and 9. The column of mercury 5 is connected by means of the conductor 12 with a binding post 13. It will be seen, therefore, that the changes 45 in the height of the mercury column due to variations in temperature will result in the closing of the circuit controlled by either one or the other of the plugs 10 and the apparatus having electrical connection therewith.

55

In the present system there is shown as running from the binding post 8 a conductor 16 connected to a magnet 17; thence running from the magnet, the conductor 16 is connected to a circuit closer 18'. The arm 18 is normally lifted, as shown, by its spring 19 against the main contact 20, from which wire 21 (a continuation of 16) is directly connected to battery 15.

60

For the purpose of illustration assume that bridge post 10 is adjusted at position 103°, then when the mercury rises to the corresponding tap 6 a circuit will be completed comprising parts 6, 10, 7, 8, and 16, magnet 17, line 16 to arm 18, through contact 20, line 21 to battery 15, thence 14 to 13, 12 and 5. The function of magnet 17 is to attract its armature 22 and thereby close a circuit, having a wire 23 electrically connected to armature 22 and running to a magnet 24, thence by wire 25 to battery 26, thence by wire 27 to anvil 28, when engaged by armature 22. The anvil 20 is provided with a set screw 28' set in a bushing 28' of hard rubber or other non-conducting material. The object of the bushing is to insulate the adjusting screw 28' from the body of the anvil so that an electric circuit will only be completed between the armature and the anvil when said armature is drawn into contact 80 with the main body of the anvil by the magnet 17. The temperature in the structure or part at which the thermometer 2 is placed having reached 103° and closed the circuit through magnet 17, whose armature 22 closes the circuit of magnet 24, then armature 25' of the magnet 24 will be attracted, and being linked at 26' to a lever or crank-shaft 27' will rock this and throw open a circuit-closing switch 28' connected to the 85 crank-shaft. The arm 28' is subject to the pull of its spring 29 to hold a carbon 30 against a stationary carbon 31. The switch arm 28' opens or closes the main heating or lighting circuit, which it is the purpose of 90 this invention to automatically control.

95

One line 32 of the circuit to be controlled

100

connects with the switch arm 28', thence to a generator 33 from which current is led by line 34 to an apparatus, in this illustration a heating medium 35 in an incubator A. 5 When the heat generated in the incubator attains 103°, the armature 25' is actuated to throw open the switch 28'. In order to mechanically and positively hold the switch 28' open, a lock consisting of a bolt 36 is 10 arranged to prevent the immediate automatic action of spring 29, and while the lock may be placed to perform its duty at any desired location, it is convenient to so dispose it that the outer end of armature 25' will be engaged by it. When the armature 25' is actuated to rock shaft 27, the bolt 36 is snapped by its spring 37 over the adjacent end of the armature, and this is then restrained against movement by spring 29, 15 20 the switch standing open. Simultaneously with the rocking of the shaft to open switch 28', the shaft carries a circuit breaker 38 against the circuit closer arm 18, thus opening the circuit of magnet 17 which was 25 energized by the thermometer at 103°. When the heating medium 35 is deenergized, the temperature will begin to fall in the incubator and at a predetermined degree, say 102°, then the opposite limb of the mercury 30 35 will operate to close a circuit through binding post 9 as the mercury reaches the tap wire at 102°. From post 9 a circuit is completed through line 40 to magnet 41, thence by line 42 to a circuit closer arm 43, which, by engagement with a contact piece 44 connected to batteries 15 by a wire 45, completes the circuit over wire 14 to the thermometer. The function of the magnet 41 is to attract an armature 54 connected by a wire 47 to a 40 magnet 48, from which runs a wire 49 leading to battery 26 or joining a line, as 25, therefrom. From battery 26 a wire 50 leads to an anvil 51, completing a circuit when engaged by armature 54. The anvil 51 is provided with a set screw 51'. The set screw is set in a bushing of non-conducting material 51' to prevent electrical connection between the parts when the armature is in its normal upper position. Manifestly, when 45 50 the temperature drops, it is necessary to again close the heating circuit at 35, so I provide the magnet 48, under control of the thermometer, to unlock the switch 28 by actuating bolt 36. The bolt has a magnetic part in the field of the magnet and upon the energization of the latter will shift against the force of its spring 37, release armature 25', and allow the spring 29 of the switch 28' to close the heating current at the contact carbons 30-31. When the shaft 27 is rocked by the closing of switch 28, the circuit closer arm 43 is moved from engagement with its contact piece 44 by a circuit breaking arm 52, thus breaking the circuit

in magnet 41. The circuit armatures 22 and 65 54 are each provided with springs 53 operating to break electrical contact with the anvils.

The several circuit-breaking and circuit-closing instruments may be provided with 70 a suitable mounting or box, as indicated at B.

Having thus described my invention, what I claim and desire to secure by Letters Patent is—

1. An electromagnetic switching system comprising a switch, an electromagnet for operating said switch, a second electromagnet for locking said switch against movement, a relay having electrical connection 80 with each of said electromagnets for making or breaking the circuits thereof, a circuit closer arm connected in series with each of said relays to make or break the circuits thereof, and an arm carried by said switch 85 for automatically actuating said circuit closer arm.

2. An electromagnetic switching system for controlling a circuit, comprising in combination, a base member, a pair of brackets 90 projecting from the base member, a shaft rotatably journaled in the brackets, an arm pivoted to one of the brackets, a contact on the base, a second contact on the arm, a lever on the shaft, an insulated link connecting 95 said arm and said lever, and means for rotating the shaft to move the lever and thereby separate the contacts.

3. An electromagnetic switching system for controlling a circuit, comprising in combination, a base member, a pair of brackets projecting from the base member, a shaft rotatably journaled in the brackets, an arm pivoted to one of the brackets, a contact on the base, a second contact on the arm, a lever 100 on the shaft, an insulated link connecting said arm and said lever, means for rotating the shaft to move the lever and thereby separate the contacts, said means comprising an electromagnet and its armature, and a 110 second electromagnet in alignment with said armature to control the movement thereof.

4. A circuit closing device comprising the combination with a circuit to be controlled, 115 of a base member, a pair of bearings secured to the base member, a shaft rotatably journaled between said bearings, an arm carried by one end of the shaft, a crank carried by the other end of the shaft, an electromagnet for operating said crank to rotate the shaft, a second electromagnet for locking said crank operating mechanism in inoperative position, relays for controlling the circuits to each of said electromagnets, a 120 circuit breaker carried by the shaft intermediate its ends, and a pair of secondary circuit closers, one in series with each of

said relays and located on each side of the shaft in operative relation with the circuit breaker to be moved thereby, said secondary circuit closers making or breaking the relay circuits when operated by the circuit breaker.

In testimony whereof I have hereunto set

my hand in the presence of two subscribing witnesses.
